UNITED STATES PATENT OFFICE

109,060

DESIGN FOR A PILLOW

Martin Henfield, Astoria, N. Y.

Application January 18, 1938, Serial No. 74,391

Term of patent 7 years

To all whom it may concern:

Be it known that I, Martin Henfield, a citizen of the United States, residing at 2546 47th Street, Astoria, Long Island, New York, county of Queens, State of New York, have invented a new, original and ornamental Design for a Pillow, of which the following is a specification, reference being had to the accompanying drawing, forming a part thereof.

I claim:

The ornamental design for a pillow as shown.

MARTIN HENFIELD.
